UNITED STATES PATENT OFFICE.

CHARLES RAYMOND COUP, OF MCKEESPORT, PENNSYLVANIA.

TOY.

1,206,106.

Specification of Letters Patent. Patented May 14, 1918.

Application filed November 24, 1917. Serial No. 203,794.

To all whom it may concern:

Be it known that I, CHARLES R. COUP, a citizen of the United States, residing at McKeesport, in the county of Allegheny and State of Pennsylvania, have invented certain new and useful Improvements in Toys, of which the following is a specification.

This invention relates to wheeled toys, of the automatically propelled type and consists in certain novel features which will be hereinafter first fully described and then more particularly pointed out in the appended claims.

In the annexed drawings:

15 Figure 1 is a side elevation of a toy embodying my present invention;

Fig. 2 is a plan view of the same;

Fig. 3 is a central longitudinal vertical section;

20 Fig. 4 is a view partly in plan and partly in horizontal section;

Fig. 5 is a front end elevation;

Fig. 6 is a detail sectional view of the spring motor.

25 My invention seeks to provide a toy which may be produced at a low cost and which when operated will simulate a moving and blowing whale. To that end I employ a body 1 which will preferably be of sheet metal and is shaped to represent a whale and provided with minute perforations 2 in its top near its front end in imitation of the blow holes of a whale. The rear end of the body is turned upwardly and given the shape

30 of a tail with the forward blade thereof disposed somewhat obliquely with respect to the longitudinal axis of the body, as shown at 3, the tail thereby serving as a rudder so that when the toy is in motion it will

35 be deflected from a straight line and caused to travel in a circular path. The body is supported upon a pair of traction wheels 4 which are carried by an axle 5 extending through the body and journaled in the sides

40 of the same, as will be readily understood, the forward end of the body being equipped on its under side with a small roller 6 so that the toy will be prevented from tipping forwardly and digging into the ground or floor

45 and thereby being prevented from moving. Motion is imparted to the axle 5 through a spring motor and suitable gearing, which may be of any well-known type but will preferably be arranged as illustrated in the 50 accompanying drawings in order to obtain compactness and to economize in the cost of

manufacture. The motor is supported within the hollow body 1 by a frame 7 secured to the inner wall of the body in any preferred manner, the axle 5 passing through 55 the side bars of said frame and having secured thereto between the bars a gear wheel 8, the said gear wheel meshing with a pinion 9 on a governor shaft 10 which is journaled in the frame 7 in rear of the axle and is 60 equipped with a weight or other simple form of governor 11 whereby an even steady motion will be attained. A pinion 12 is also secured upon the axle 5 and this pinion meshes with a gear wheel 13 on a counter-shaft 14 which also carries a pinion 15 65 meshing with the driving gear 16. The gear 16 is secured upon the motor shaft 17 which is journaled at one end in the frame 7 and at its other end is loosely fitted in the motor 70 casing 18 from the side of which a winding shaft 19 extends through the side of the body 1, and said winding shaft is provided at its outer extremity with a key or handle 20, as will be readily understood. Within 75 the casing 18 is coiled a spring 21 having one end secured to the motor shaft 17 and its outer end secured to the rim of the motor casing 18. A series of ratchet teeth 22 is provided upon the outer end of the casing 80 18 and a pawl 23 is secured upon the frame 7 adjacent said casing to engage the said ratchet teeth and thereby prevent retrograde movement of the casing. When the toy is 85 to be operated, it is held in one hand with the fingers of said hand grasping the traction wheels 4. The key or handle 20 is then rotated so as to turn the casing or drum 18 in the direction indicated by the arrows in Fig. 6, causing the ratchets 22 to ride over 90 the pawl 23 and the coils of the spring 21 to be tightened. The pawl by engaging the ratchets will prevent reverse rotation of the drum or casing and therefore when the toy is placed upon the floor or ground and the 95 wheels 4 released the spring will at once expand and will exert a pull upon the motor shaft 17 which will cause the same to rotate in the same direction as the casing was rotated in winding the spring. The 100 gears 16 will, of course, rotate with the motor shaft and will impart motion to the counter-shaft 14 through the described gearing and the said gearing will in turn cause the axle to rotate in the proper direction to 105 propel the body forward.

In the front end of the body 1, I provide

2 a reservoir 24 the walls of which will be constructed of some flexible material, and this reservoir is provided in its upper side with openings in one of which is fitted a discharge tube 25 having its upper end registering with the perforations or blow holes 2 and its lower end disposed near the end of the body of the reservoir. In the other opening, a filling tube 26 is secured and said filling tube extends through the top of the body and is adapted to receive a cork or other closing plug, indicated at 27, whereby it will be closed against the access of air after the reservoir has been filled with water. 5

10 Slightly fitted in the frame 7 is a plunger 28 having a head or presser plate 29 at its front end in contact with the rear wall of the reservoir 24. The rear end of the plunger 28 is formed into an eccentric ring fitting around the eccentric or cam 30 secured upon the inner end of the motor shaft 17. 15

15 When the toy is to be used the reservoir 24 is filled with water poured through the filling tube 26 and the plug 27 is then fitted 20 in the outer or upper end of said tube so as to close the same. The spring having been wound and the toy placed upon the floor or ground, the motor will at once propel the body forward and, as the motor shaft 17 rotates, the plunger 28 will be reciprocated 25 through the action of the eccentric or cam 30. The reciprocation of the plunger will cause the reservoir 24 to be alternately compressed and expanded and when it is compressed a portion of the liquid therein will 30 be expelled through the discharge tube 25 and will escape through the perforations 2 in the form of fine streams, as indicated in Fig. 1. As the plunger recedes from the 35 reservoir, air will flow in through the perforations 2 and will cause the reservoir to expand, the air rising to the top of the same 40

and exerting a pressure upon the liquid therein so that upon the next compression stroke of the plunger liquid will be again expelled, and this operation will be repeated until every drop of the liquid has been driven from the reservoir. My improved toy can obviously be produced at a very low cost and when in action the imitation of a whale in the act of blowing or spouting will be very natural and will be conducive of considerable amusement. The body of the toy may be entirely closed except for the filling and discharge openings over the reservoir so that the motor will not be accessible and consequently cannot be put out of order by the tampering of curious children or other persons. 55

Having thus described the invention, what is claimed as new is:

1. A wheeled toy comprising a hollow body having a filling opening and a discharge opening in its top near its front end, a reservoir within the body having flexible walls and having its top in communication with the said filling and discharge openings, a motor within the body in rear of said reservoir, and a plunger actuated by said motor and bearing upon the reservoir. 70

2. A wheeled toy comprising a hollow body having filling and discharge openings in its top near its front end, tubes depending within the body around said openings, a flexible reservoir secured around the said tubes, a closure for the upper end of the filling tube, a plunger bearing upon the rear side of the reservoir, and a motor within the body for reciprocating said plunger, the discharge tube having its lower end disposed near the bottom of the reservoir. 75

In testimony whereof I affix my signature.

CHARLES RAYMOND COUP.
